UNITED STATES PATENT OFFICE.

FRANK H. GIBBS, OF PORTLAND, OREGON.

DISPLAY-CABINET.

1,330,181.

Specification of Letters Patent. Patented Feb. 10, 1920.

Application filed April 15, 1919. Serial No. 290,170.

To all whom it may concern:

Be it known that I, FRANK H. GIBBS, a citizen of the United States, residing at 865 Clinton street, Portland, in the county of 5 Multnomah and State of Oregon, have invented certain new and useful Improvements in Display-Cabinets, of which the following is a specification.

The present invention relates to improvements in display cabinets in the class of 10 store furniture, and particularly to a swinging drawer construction or structure forming part of the cabinet, whereby the drawer may be swung outwardly, entirely free from 15 the cabinet, and detached from its swinging bracket hanger, and may with equal facility be attached again to the bracket hanger, and returned to normal position within the confines of the cabinet.

20 The primary object of the invention is the provision of a piece of store furniture including drawers in which the merchandise is stored, said drawers not only having glass fronts to render the contents of the drawers 25 visible but in addition the drawers may be swung free from the cabinet, and then detached bodily therefrom so that the merchandise contained in the detached drawer may be inspected and is accessible for sale.

30 The invention consists in certain novel combinations and arrangements of parts involving a detachable drawer, a swinging bracket hanger for the drawer, and certain other novelties in connection therewith as 35 will be hereinafter more fully described and claimed.

In the accompanying drawings one complete example of the physical embodiment of the invention is illustrated, the parts being 40 combined and arranged according to the best mode so far devised for the practical application of the principles of the invention.

Figure 1 is a front elevation of the revolving cabinet or case involving the new arrangement of swinging drawers, part of the figure being broken away for convenience of illustration.

Fig. 2 is a horizontal sectional view on 45 line 2—2 of Fig. 1.

Fig. 3 is an enlarged, sectional view showing one of the drawer hangers, from the inside of the cabinet, and a drawer supported in the hanger.

Fig. 4 is a top plan view of a portion of 55 a drawer showing the manner of hooking it onto the bracket hanger, and showing also the bracket hanger against one of the corner posts of the cabinet to prevent further swinging movement of the hanger.

Fig. 5 is a sectional view of the back wall 60 of the drawer and hanger showing the hook in position, at line 5—5 of Fig. 3.

Fig. 6 is a section of the front of the 65 drawer on line 6—6 of Fig. 2.

In the preferred form of the invention I have employed a revoluble cabinet or case in which the drawers are hung and from which they may be swung, but it will be understood that the drawers and their attachments form the essential features of the invention and that the drawers may be used in other modes or structures, than the revoluble cabinet.

The cabinet is supported upon a cruciform base, which has a center column 2, that may be an iron pipe, seated and fixed in the socket plate 3 at the center of the base, and at the upper end the column is provided with a bearing head 4 forming part of a ball 70 bearing suspension for the cabinet or case indicated as a whole by the numeral 5.

The revoluble cabinet is fashioned with a closed bottom 6 that may be of wood or metal, and a top board 7, which parts are 75 connected by the corner posts 8, that are connected with and braced by the horizontal ribs 9. The cabinet thus is formed of a skeleton frame, and illustrated in the form of a decagon or ten-sided figure with spaced 80 corner posts and spaced horizontal ribs, and the skeleton frame is braced by the suspension rods 10 which extend from the bearing head 11 at the center and underside of the top board 7, outwardly and downwardly to 85 the periphery of the bottom or floor 6 of the cabinet. The cabinet is thus free to revolve on the fixed base 1, and at 12 a guide plate 90 is indicated in dotted lines (Fig. 1) for steadyng and guiding the revoluble cabinet 95 in its movement.

Adjacent each of the corner posts of the cabinet frame is located a hinge bar 13 extending from the base to the top of the cabinet, and fixed in position to support the 100 swinging drawers 14 that are located in the spaces formed by the horizontal ribs and corner posts of the cabinet.

A multiplicity of drawers are illustrated, but they are all of similar construction and supported from the hinge bars 13, so that a description of one drawer will be sufficient for all of them.

Each drawer is detachable, and may be bodily removed from the cabinet, but is suspended, when in normal position from a swinging bracket hanger 15 hinged on the hinge bar 13, and supported on the fixed bearing bracket 17, one of which is fixed in the rib 9 directly beneath each hinge joint 16 and serves as a bearing support for the bracket hanger to swing on. The bracket hanger and the bearing bracket are of metal, and the long hinge joint 16 of the hanger on the hinge bar, permits the horizontal bracket to hang true and without sagging, and to support the drawer, preferably on a flange 20 or shelf 18 projecting from the bottom of the bracket hanger a sufficient distance to support the drawer.

The free end 19 of the hanger bracket is positioned to abut against the corner post 8 and prevent the bracket from swinging out of the cabinet, but, as in Fig. 2, the drawer may be swung out entirely beyond the outer face of the cabinet. The drawer 14 is attachable and detachable with relation to its bracket hanger, and for this purpose is provided with an elongated hook 20 made of a single piece of wire bent to shape and adapted to engage over the top edge of the hanger or bracket, and fit neatly and tightly, with frictional contact with the bracket. In the upper edge of the hanger bracket, spaced notches 21 may be arranged to seat the bars of the hook, and the hook itself is rigidly secured to the back wall of the drawer by

eyes 22 on bolts or screws in the wall 23 of 40 the drawer.

The front of the drawer has a glass plate 23' to render the interior of the drawer visible, and a handle plate 24 may be used when opening or closing the drawer, and also as 45 a name plate for the contents of the drawer.

What I claim is—

1. The combination of a drawer, a hanger bracket consisting of an elongated strip against which one side of the drawer is disposed having its ends projecting beyond the drawer, a vertical hinge bar about which one end of the bracket is bent to form a hinged connection, a flange along a portion of the lower edge of the hanger bracket upon which the drawer rests, and a spring clasping member carried by the upper edge of one side of the drawer and engageable with the upper edge of the said hanger bracket, as described. 60

2. The combination of a drawer, a vertical hinge bar at one side thereof, a stop at the opposite side, a hanger bracket along one side of the drawer having one end swingingly mounted on the hinge bar and having its opposite end projecting beyond the drawer to engage said stop, said hanger bracket having a lower flange on which the drawer rests and provided with notches in its upper edge, and a clasping member engaging the upper edge of the hanger bracket and formed of a V-shaped wire, the side members of which are seated in the said notches to prevent displacement of the drawer lengthwise of the hanger bracket. 65 70 75

In testimony whereof I affix my signature.
FRANK H. GIBBS.
